[57] **CLAIM**

The ornamental design for a bird feeder, substantially as
shown and described.

DESCRIPTION

FIG. 1 is a perspective view taken from the top, front
and right side of a bird feeder showing my new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a right-side elevational view thereof; and
FIG. 7 is a left-side elevational view thereof.

FIG. 1

FIG.2

FIG.4

FIG. 5

FIG. 3
